UNITED STATES PATENT OFFICE.

FREDERICK W. LUSCOMB AND DAVID A. COREY, OF NEW BEDFORD, MASSACHUSETTS, ASSIGNORS TO THE APPLEGATE BOOT AND SHOE LASTING COMPANY, OF PORTLAND, MAINE.

LASTING-MACHINE.

SPECIFICATION forming part of Letters Patent No. 393,772, dated December 4, 1888.

Application filed January 27, 1888. Serial No. 262,117. (No model.)

To all whom it may concern:

Be it known that we, FREDERICK W. LUSCOMB and DAVID A. COREY, of New Bedford, county of Bristol, and State of Massachusetts, have invented an Improvement in Lasting-Machines, of which the following description, in connection with the accompanying drawings, is a specification, like letters on the drawings representing like parts.

10 This invention has for its object to improve the construction of a lasting-machine invented by Russell Hathaway and Elbridge G. Paull and described in application Serial No. 262,148, filed on the 27th day of January, 1888, the said 15 machine containing hooks or draw-bars adapted to be engaged with cords, thongs, or wires arranged in pockets or otherwise connected to the upper, so as to draw or shirr the upper.

The improvements in the machine to be 20 herein described over the Hathaway and Paull machine relate to the jack to hold the last, to the construction of the toe-rest and the manner of adjusting it, to the levers and the means for operating them, and to the connections 25 and the manner of attaching them to the levers, and to the arrangement of the treadles, and the combination, with the treadles, of means for locking them in adjusted position, as will be described.

30 Figure 1 is a top or plan view of a lasting-machine embodying our invention. Fig. 1^a shows developed the cam-block and cam-ring of the jack mechanism. Fig. 2 is a left-hand end elevation of the machine shown in Fig. 1, 35 some of the parts being broken out to better illustrate the construction and to show other parts back of them. Fig. 3 is a sectional detail in the line x, Fig. 2. Fig. 4 is a section in the line x', Fig. 2. Fig. 5 is a section in 40 the line x², Fig. 2. Fig. 6 is a sectional detail showing the manner of connecting the rods C' and a³ to the arms and treadles, and Fig. 7 is a section of Fig. 2 below the dotted line x⁵.

The bed A of the machine, supported upon 45 suitable legs, A', has at its ends suitable bearings, as a, for the reception of the rock-shafts, as A². Each rock-shaft has secured to it by a set-screw, a', an elbow-shaped arm, a², the inner free end of which is connected by a link,

a³, with a treadle, a⁴, made as a lever, having 50 its fulcrum on a rock-shaft, B, the ends of which outside the collars B' enter loosely within bearings, as B², forming part of or secured to the legs or uprights A', constituting the ends of the machine.

55 The arms a² have mounted adjustably upon them weights a⁵, which normally act to turn the shafts A² in a direction opposite that which they may be turned by the operator by placing his foot upon the free outer end of the 60 treadle a⁴, there being two such treadles and connections to actuate the arms and rock-shafts at opposite ends of the machine.

The rock-shafts A² have keyed or secured 65 to them in suitable manner blocks or holders b, grooved at their outer sides to receive the lower ends of like upright levers, b', each lever receiving through it at its lower end a screw-stud, as b², which serves as a pivotal point for the lever.

70 Each holder has a pin, as b³, which is preferably covered with india-rubber to prevent noise, the said pin serving as a stop to determine the outward position of the lever b', acted upon by a hollow block, as b⁵, (see Fig. 1,) 75 which is normally pressed outward by a spiral spring, as b⁶.

Each rock-shaft A² serves as a pivot for an elbow-shaped lever, C, the inner end of which is joined by a connecting-rod, as C', to the 80 outer end of an arm, as C² C³, fixed to the shaft B, the said arm C² C³ and shaft B constituting a treadle by which, through the said rods C', to actuate in unison the two levers C. The hub of the lever C, the shape of which is 85 best shown in the sectional detail, Fig. 5, has its outer side planed or made smooth, as at c, to receive against it the inner side of a holder, c', which is held frictionally against the smooth outer face of the said hub by a clamping-bolt, c³, having a handle, c⁴, the said clamping-bolt enabling the holder to be adjusted 90 more or less out of vertical line with relation to the front and back of the machine, so as to enable the lever c⁵, pivoted upon a pin, c⁶, held in the said holder, to be placed in the proper position with relation to the toe part of the boot or shoe to be lasted, the adjustment for 95

ward and backward of the levers c^5 adapting the machine for use in connection with shoes of different length.

The holder c' has a stop similar to the stops b^3 employed in connection with the holders b ; but the lever c^5 is normally pushed outward against the said stop by a strong flat spring, as c^2 , the lower end of the said spring being secured to the holder by one or more screws, as shown in the said figure.

The table A has secured to it at its upper side a track, D, the upper side of which is beveled to form an inclined plane, the sides of the track being provided at each side with a groove, d , parallel with the top of the track. This track is embraced by a carriage, D', provided at its under side at each side the track with a flange, d' , which enters the grooves d , the said flanges and grooves preventing the carriage from being lifted off the track in its movements thereon. The upper side of the track is grooved for the reception of a rack, as D², which will preferably be made from steel for great endurance.

The carriage D' has rising from it a hollow post (shown broken out in Fig. 2) to receive a screw, d^3 , to the upper end of which is fixed or attached the toe-rest d^4 , the said toe-rest being covered, preferably, with a leather or other suitable pad to prevent marring the upper of the shoe. The threaded part of the screw d^3 is extended through a nut, d^4 , having a milled or other enlarged head, 2. To support this nut so that it will sustain great strain, the hollow portion of the carriage has been provided with a shoulder, as at 3, upon which the lower end of the nut d^4 rests at the same time that the under side of the milled head 2 bears against the outer end of the hollow upright. This screw and nut may be readily lifted from the carriage whenever the shoe is out of the machine and the nut be quickly turned to enable the toe-rest to be set to approximately the proper height; but after the toe-rest has been applied to the hollow post and the shoe to be lasted has been applied to the toe-rest then the nut may be readily turned by grasping its milled head 2 until the toe-rest has been placed at exactly the proper height or level.

The carriage D' has bearings for the short shaft e , upon which is secured within the carriage and below the screw d^3 a pinion, e' , which engages the rack D², the outer end of the said shaft e having fixed to it a hand-wheel, e^3 , rotation of which enables the pinion in engagement with the rack to move the carriage longitudinally toward and from the heel-rest to be described, and in its movement the said carriage and toe-rest are carried up and down the inclined plane at the top of the track D, the incline being such as to enable the toe-rest to be maintained in correct working position with relation to the curvature of the top of the last, notwithstanding the length of the last. The carriage D' also has a set-screw, as e^4 , which may be screwed in against a gib, as

e^5 , preferably of brass, to prevent any longitudinal movement of the carriage, except when being moved through the operator engaging the hand-wheel e^3 .

The heel-pin is composed of two parts, the upper part, f , being pivoted to the lower part, f' , by a screw or other stud, f^2 , the lower part, f' , being fixed to or rising from a cam-block, f^3 , fixed to the bed A. (See Figs. 1^a and 2.)

The part f' of the heel-pin receives loosely upon it above the block f^3 the cam-ring g , and upon the top of the said cam-ring is placed loosely a steel annulus, g' , which, when elevated upon the part f' by the rotation of the cam-ring g , it resting on the cam-block f^3 , meets the beveled toe 6 at the lower end of the upper portion, f , of the heel-pin and tips the said portion f upon the pivot f^2 , the upper portion of the heel-pin being at such time positively moved forward toward the toe-rest for a short distance, or far enough to firmly impinge the upper upon the toe-rest through the action of the last, the latter being thus firmly locked in position before the operator commences to draw the upper over upon the bottom of the last or the inner sole laid thereon, thus preventing any tendency of the last to twist or turn out of correct position.

The upper side of the cam-block f^3 and the lower side of the cam-ring g , provided with a handle, g^2 , (shown in Fig. 1,) have each one or more cam-surfaces, as 8 9, and a horizontal or plane surface, as 10 12, so that while the nut is moved for a portion of a rotation the two cam-surfaces, being in contact, will lift the ring and annulus quickly; but as soon as the plane surfaces 10 and 12 come in contact, and while so in contact, the cam-ring cannot recede or turn backward by reason of any weight or downward pressure applied to it or by reason of a stroke or blow on the last, as would be the case if both cam-surfaces extended entirely around the cam block and ring.

The upper h of the shoe to be lasted has applied to it about its lower edge a draw-cord, thong, or wire, as l , the said draw-cord being extended through channels or pockets composed, as herein shown, of loops h^3 of thread, the said loops and draw-cord, when put together in the shoe, resembling and constituting practically what is known as a "lock-stitch," the said loops and draw-cord being put in, if desired, by a sewing-machine having an eye-pointed needle and a shuttle. It will be understood that this draw-cord may be connected with the upper of the shoe in any usual way, either as herein shown or as shown in United States Patent No. 248,566, dated October 25, 1881, to J. H. Applegate. The upper having been prepared in this way and placed upon the last h' , the usual inner sole, h^4 , is applied, as shown in Fig. 1, and the last will be jacked firmly in place by turning the handle g^2 and nut d^4 . The levers b' c^5 at their upper ends (see Figs. 2 and 5) have applied to them loops or slides m , which are held in adjusted position therein by suitable

set-screws, *o*. The loops or slides *m* are notched or cut away at their inner sides, (see Fig. 4,) so as to receive between them and the said levers and engage and hold the outer ends 5 of the flexible connections *n* *n'* *n''*, (shown as a chain,) the opposite ends of the said connections having attached to them like weighted heads or swivels, *n*², to which in turn are connected the hooks or draw-bars *n*⁴ *n*⁵ *n*⁶, the 10 hooks or draw-bars being adapted to engage the cord, thong, or wire *t* to last the toe, the hooks or draw-bars *n*⁵ engaging the draw-cord, thong, or wire near the ball of the last, while the hooks or draw-bars *n*⁴ engage the draw-cord 15 nearer the heel, all as shown in Fig. 1. The shoe having been jacked, the hooks or draw-bars are seized by hand and hooked on the draw-cord, the operator at such time moving the levers *b* and *c*⁵ against the springs *b*⁶ 20 and *c*⁷, the said springs normally acting to insure the engagement of the hooks and draw-cord when the operator removes his hand from the hooks. In this condition the operator depresses the treadle *C*³ and lasts the toe, or 25 nearly so, and then by putting the foot on the treadles *a*⁴ the levers *b*⁷ are moved to last the upper along the full shank and heel.

Each lever or foot-treadle has co-operating with it a locking device, *r'*, shown as a ratchet-toothed spring-held bar pivoted at 20, the said teeth engaging the edge of a plate, 23, attached to the lever or treadle and holding the lever or treadle in the position left by the operator after removing his foot. This hooked bar at 35 its lower end has a lug, 21, which is acted upon by a spring, 22, and the upper end of the bar at its rear side is acted upon by a pin, 24, normally pressed outwardly against the bar by a spring, 25. Each lever or treadle 40 has mounted upon it a releasing device, as *r*, the said releasing device being herein shown as pivoted at 26, and of such shape that the operator with his foot upon the treadle may turn the releasing device to push the locking device backward against the spring; and thus 45 release the lever or treadle in order that it may be moved.

In practice the upper and lower ends of the connecting-rods *C'* and *a*³ are made ball shape, 50 as shown in the sectional detail, Fig. 6, the said ends entering sockets in the arms and in the levers and treadles, the said ends being retained in the said sockets by clips, as 29, attached to the rods by screws 30.

We do not herein claim nippers to engage the material of the upper, the said nippers being attached by flexible connections to levers by which the upper is drawn over upon the inner sole; but in our invention the hooks 55 or draw-bars in all instances will be so constructed as to engage the shirr cord, thong, or wire. The strain put upon the upper to fit it upon the last and to draw its edge over upon the inner sole is exerted through the said cord *t*. 60 In practice the toe part of the upper will first be lasted, and then the ball and shank, and both sides may be drawn to the last simul-

taneously, or either side may be drawn separately by means of the foot-treadles.

We do not herein broadly claim a series of 70 arms, as *b'* and *c*⁵, nor do we broadly claim a toe-rest made movable on an inclined track, nor do we broadly claim a vertically-adjustable heel-pin.

We do not claim anything shown in the 75 application of the said Hathaway and Paull. In our application the carriage containing the toe-rest may be slid on the inclined track, and all the arms or levers to which are joined the connections under the control of treadles are 80 readily accessible to the foot of the operator leaving his hands free to manipulate the hooks or draw-rods and the upper.

We claim—

1. In a lasting-machine, a pivoted lever, as 85 *b'*, the loop or slide thereon, and connection *n*² and attached swivel, combined with the hook or draw-bar, substantially as described.

2. In a lasting-machine, the rock-shafts *A*², 90 their attached holders *b* and arm or lever pivoted thereon, and spring, combined with the hook or draw-bar and means to connect it to the said arm or lever, substantially as described.

3. In a lasting-machine, the shafts *A*², the two 95 levers *C* thereon, the holders *c'*, adjustably attached to the hubs of the said levers, and the levers or arms *c*⁵, pivoted in the said holders, and the springs, combined with the hooks or draw-bars and intermediate connections between them and the said arms or levers, substantially as described.

4. In a lasting-machine, the shafts *A*², the two levers *C* thereon, the holders *c'*, adjustably attached to the hubs of the said levers, 105 and the levers or arms *c*⁵, pivoted on the said holders, and the springs, combined with the hooks or draw-bars and intermediate connections between them and the said arms or levers, and with a connecting-rod and foot-treadle to actuate the said levers, substantially as described.

5. In a lasting-machine, the two rock-shafts *A*², their attached arms and holders *b*, levers, connections, and hooks or draw-bars, combined 115 with the links and two foot-treadles arranged at the front of the machine side by side, so as to be simultaneously operated by foot, substantially as described.

6. In a lasting-machine, the shafts *A*², the two levers *C* thereon, the holders *c'*, adjustably attached to the hubs of the said levers, and the levers or arms *c*⁵, pivoted in the said holders, and the springs, combined with the hooks or draw-bars and intermediate connections between them and the said arms, and with weights hung on the said arms, substantially as described.

7. In a lasting-machine, the inclined track grooved on its upper side, the rack therein, 130 and the carriage, combined with the toothed wheel engaging with said rack, rotation of which moves the said carriage on the said track, substantially as described.

8. In a lasting-machine, the carriage having a shoulder and means to support the carriage, combined with the toe-rest having a screw-threaded shank, and with the nut having a head or flange, 2, the said nut being sustained loosely by both the said shoulder and the upper end of the said carriage, substantially as described.

9. In a lasting-machine, the jack provided with the heel-pin composed of two parts, one pivoted on the other and provided with a beveled or inclined toe, combined with a loose collar and with the cam-block and cam-ring, each having cam portions and plane surfaces, to operate substantially as described.

10. In a lasting-machine, the heel-pin com-

posed of two parts, one pivoted on the other and having a beveled or inclined toe, a loose collar, and the cam-block to move the collar to act on the said toe, combined with the vertically-adjustable toe-rest, the carriage to support it, and the inclined track on which the said carriage is adjustable, substantially as described.

In testimony whereof we have signed our names to this specification in the presence of two subscribing witnesses.

FREDERICK W. LUSCOMB.
DAVID A. COREY.
